UNITED STATES PATENT OFFICE.

JAMES C. DAWSON, OF WEBSTER GROVES, MISSOURI, ASSIGNOR TO ELMA N. DAWSON,
OF WEBSTER GROVES, MISSOURI.

LOOSE-LEAF BINDER.

Application filed March 21, 1924. Serial No. 700,811.

To all whom it may concern:

Be it known that I, JAMES C. DAWSON, a citizen of the United States, and resident of Webster Groves, county of St. Louis, and 5 State of Missouri, have invented certain new and useful Improvements in Loose-Leaf Binders, of which the following is a specification, and which are illustrated in the accompanying drawings, forming a part 10 thereof.

This invention relates to loose leaf binders and has for its principal object to reduce the cost of production by providing a simple structure that permits the parts to 15 be easily formed and assembled. Further objects and advantages of the invention will become apparent as the disclosure proceeds and the description is read in connection with the accompanying drawing, in which—

20 Fig 1 is a fragmentary perspective view of a binder embodying the invention;

Fig. 2 is a plan view of a blank from which the base member of the paper holding devices is formed;

25 Fig. 3 is a fragmentary sectional view taken on the line 3—3 of Fig 1,

Fig. 4 is a cross section taken on the line 4—4 of Fig. 1.

The binder may include a pair of covers 30 10 and 11 hinged to a back 12 upon which are secured leaf retaining devices forming the subject matter of this invention.

These devices include a base 13 and a rock shaft 14 having hooks 15 at its ends that 35 are received in perforations in the sheets to be retained. The base is preferably formed up from a blank illustrated in Fig. 2 by bending the side edges downwardly along the lines 16 and 17 to form flanges 18 and 19 and by bending the ends along the lines 20, 21, 22 and 23 to form the downwardly extending end flanges 24 and the tabs 25. The lines 16 and 17 are spaced from the side edges 26, 27, 28 and 29 of the end projections on the blank and therefore the side flanges 18 and 19 are likewise spaced from the edges 30 and 31 of the end flanges 24. The rock shaft 14 lies along the flange 18 and this flange cooperates with the edges 31 45 to form bearings in which the shaft is journaled. The flange 18 is preferably notched adjacent to its ends, as indicated at 32 and 33, and the end portions 34 are bent, as indicated at 35, Fig. 4, to extend slightly under the rounded surface of the rock shaft 14.

These bent portions may be of only very small extent for they are relied upon chiefly to prevent displacement of the shaft while the leaf holding devices are awaiting attachment to the back 12. After they are 60 thus assembled by means of rivets 37, the flange 18, and the edges 31 of the flanges 24 are sufficient bearings for the shaft.

End play of the shaft is prevented by contact of the hooks 15 with the shoulders 65 formed by the ends of the flange 18 and the aligned edges 36 of the body portion which preferably remains substantially flat.

The hooks 15 have notches 38 adjacent to their free ends which serve as catches to 70 engage the base at the shoulders 39. The spacing between the lines 16 and the edges 27 and 29 makes these shoulders sufficiently wide to accomodate the hooks, but the corners of the flange 19 may be cut away as 75 indicated at 40 on the blank, Fig 1, to prevent any interference with the proper engagement of the hooks.

From the foregoing it will be clear that 80 the paper holding devices embodying this invention may be made with a minimum of material and require only simple forming operations that may be accomplished at low cost. The assembly of the rock shaft with the base is easily accomplished and the bearings for the shaft, while ample for all purposes and use, require no expensive forming operations.

I claim as my invention:

1. A temporary binder comprising side 90 covers and a connecting back portion, a sheet metal base fixed to the back portion, including flanges extending downwardly from the sides of the base, a tab including a downwardly extending portion at one end 95 of the base, having its edges spaced from the flanges, a rock shaft journaled between one of the flanges and the edge of the downwardly extending portion of the tab, and a hook carried by the rock shaft having a 100 catch for engagement with the base adjacent to the opposite side.

2. In a temporary binder, a sheet metal base having downwardly extending flanges at each side, a tab at one end including a 105 downwardly extending portion having one edge spaced from the corresponding flange, a rock shaft between said edge and flange, the bottom portion of the flange being bent inwardly under the rounded surface of the 110

shaft and binding it against said edge, and a hook on the shaft having a catch for engagement with the base.

3. In a temporary binder, a sheet metal base having downwardly extending flanges at each side, a tab at each end including a downwardly extending portion having each edge spaced from the corresponding flange,

a rock shaft journaled between one side flange and the adjacent edges of the tabs, and hooks on the rock shaft having catches for engagement with the base between the other side flange and the corresponding edges of the tabs. 10

JAMES C. DAWSON.
